ATTORNEY

UNITED STATES PATENT OFFICE.

SIMON TOFFLER, OF NEW YORK, N. Y.

GRATER.

SPECIFICATION forming part of Letters Patent No. 230,679, dated August 3, 1880.

Application filed April 30, 1880. (No model.)

To all whom it may concern:

Be it known that I, SIMON TOFFLER, of the city, county, and State of New York, have invented certain new and useful Improvements 5 in Graters, of which the following is a specification.

In the accompanying drawings, Figure 1 represents a top view of my improved grater, with a part broken off; and Fig. 2 is a side 10 view of the same, partly in section.

Similar letters of reference indicate corresponding parts.

The object of this invention is to furnish for household and other purposes an improved 15 grating implement, by which the operation of grating is accomplished easier and quicker, which is stronger and less liable to wear, and capable of being cleaned with greater facility and convenience than the common graters in 20 general use.

The invention consists of a main piece or plate provided with a series of projecting pins or teeth, and of a hinged and perforated clearing-plate, which is fitted to the pins and main 25 plate and adapted to be thrown back for easier cleaning.

In the drawings, A represents the main piece or plate, of wood, cast-iron, or other suitable material. The main plate A is provided at 30 one end with a handle, a, and at the opposite end with supporting-legs b b. The middle or main portion of the main plate is provided with a series of projecting pins, d, of metal, which are either driven, cast, or otherwise secured into the plate A. Over the middle toothed portion of the plate A extends a perforated clearing-plate, B, which is preferably 35 hinged to the plate at the handle end, so as to be thrown up and back over the handle. The 40 perforations d d are so arranged that they fit over pins, the holes being of sufficient size to admit the clearing of the projecting pins in swinging back the clearing-plate or in placing it in position over the pins. The clearing- 45 plate B has downwardly-bent side flanges, e e, which serve to secure the clearing-plate on

the main plate when it is placed into position thereon. The pins project above the clearing-plate and act with great force upon the article to be grated, being less liable to wear than the 50 punched-up teeth of the common sheet-metal graters in general use.

The series of teeth exert a more powerful grating-action, while by the use of a larger grating-surface the operation is performed 55 quicker.

When the grating is accomplished the clearing-plate is lifted from the pins, so as to remove all the adhering gratings therefrom, and then both the perforated plate and the teeth 60 cleaned with great facility.

I am aware that perforated cleaning-plates have been employed in curry-combs, brushes, and similar articles; but in one case the main plate or back is not solid, but perforated, and 65 in the other case the clearing-plate can only be raised to a certain distance from the main plate and not replaced when removed entirely from the brush. Neither device can be used as a grater, which is the main object of this 70 invention.

Having thus described my invention, I claim as new and desire to secure by Letters Patent—

1. A grater composed of a solid main plate 75 having projecting pins or teeth, and of a perforated clearing-plate, which is adapted to be placed over the pins and to be removed therefrom, substantially as set forth.

2. As an improvement in graters, the combination of a solid main plate having projecting pins or teeth with a perforated clearing-plate hinged to the former, substantially as described.

In testimony that I claim the foregoing as 85 my invention I have signed my name, in presence of two witnesses, this 21st day of April, 1880.

SIMON TOFFLER.
